CONVERTIBLE STORM SASH AND WINDOW SCREEN

Anthony Gimmelli, Waterbury, Conn.

Application March 29, 1938, Serial No. 198,626

6 Claims. (Cl. 20—55)

This invention relates to windows, and more particularly to a convertible storm window and fly screen.

One object of this invention is to provide a convertible storm sash and screen of the above nature employing a pair of interchangeable metal frames for holding the storm window glass and the screen, respectively, and in which said frames may be interchanged without requiring special tools or the services of a skilled workman.

A further object is to provide a device of the above nature in which provision is made of a common receiving and holding frame into which the glass-holding frame and screen-holding frame may be selectively inserted and secured.

Another object is to provide a combined storm sash and window screen of the above nature having improved means for locking the selected glass-holding or screen-holding frame in position in the common receiving frame.

A still further object is to provide a combined storm sash and window screen of the above nature which will be simple in construction, inexpensive to manufacture, compact, ornamental in appearance, and very efficient and durable in use.

With these and other objects in view there has been illustrated on the accompanying drawing one form in which the invention may be conveniently embodied in practice.

In the drawing:

Fig. 1 is an outside elevational view of a window, showing the storm sash in assembled position thereon.

Fig. 2 is a fragmentary sectional view on a larger scale of the common receiving frame, the section being taken along the line 2—2 of Fig. 1.

Fig. 3 is a sectional view similar to Fig. 2, and showing a fly screen substituted for the storm sash.

Fig. 4 is a sectional view of the common frame on a still larger scale as it appears when the glass-holding frame is mounted therein.

Fig. 5 is a view similar to Fig. 4, showing the appearance of the common frame when a fly screen is mounted therein.

Fig. 6 is an enlarged front view of a portion of the storm sash-holding frame.

Fig. 7 is an enlarged top view of a portion of the resilient screen securing strip.

Fig. 8 is a perspective view of a glass securing clip.

Fig. 9 is a perspective view of a hook member for selectively securing either the sash-holding frame or screen-holding frame to the common receiving frame.

Referring now to the drawing wherein like reference characters denote corresponding parts throughout the several views, the numeral 10 designates a window frame of standard construction, and to which a common receiving frame 11,

preferably of wood or molded composition, is pivotally secured at its upper end by means of hinges 12. The common frame 11 is provided in its bottom rail 14 with slots 13, which are preferably metal lined and serve to permit water to drain from the frame 11.

Provision is made of a pair of sash-holding and screen-holding frames 15 of identical shape, preferably constructed of sheet copper, which are provided with convexly curved front flanges 18 adapted to overlie similarly shaped convex beads 16 extending along the inner edges of the four openings 17 of the common frame 11. Each of the copper frames 15 (see Figs. 4 and 5) comprises a convex flange 18 shaped to fit the forwardly directed beads 16 on the edges of the common receiving frame 11, a short lip 19 formed by bending the metal back upon itself, a web 20 adapted to extend over the edge of the opening 17 at right-angles to the lip 19, and an inwardly extending short flange 21, the latter being somewhat greater in length than said lip 19.

To seal the flanges 18 to the beads 16 a strip of sponge rubber 22 or the like is disposed between these parts and suitably cemented to said beads.

The rubber strips 22 are adapted to be compressed in the receiving frame 11 by the metal frames 15. The metal frames 15 are detachably secured to the common receiving frame by means of a plurality of spaced hooks 23 pivoted to the inside of the openings 17, as by rivets 24. The hooks 23 are adapted to engage under the heads of screws or pins 25 rigidly mounted in said openings 17 and protruding therefrom as shown. By means of this construction, it will be understood that by unfastening the hooks 23 from the pins 25, the metal frames 15 may be readily removed from the wooden receiving frame 11 and another frame 15 holding a screen 27 or other type of panel may be substituted therefor without the use of special tools. This construction facilitates the rapid conversion of a winter storm sash into a summer screen or vice versa.

In order to detachably receive either the pane of glass 26 or the screen 27, the lips 19 are provided with a series of elongated perforations or slots 28, spaced along the edges of the receiving frame 11, as indicated in Fig. 1. After a pane of glass 26 has been assembled in the frame 15, special tapered clips 29 (see Fig. 8) will be inserted in each of the slots 28. The clips 29 are preferably made of metal and each has an end lug 30 adapted to fit into the slot 28. The wide ends 31 of the tapered clips 29 are rounded and adapted to lie under the edge of the plate of glass 26 in the frame 15 in engagement with said flange 21 (see Fig. 4). For the purpose of pressing the glass plate 26 resiliently against the flange 21, each of the tapered clips 29 is provided with an offset tapered flange 32 with its high point located 60

adjacent the surface of the glass 26. The clips 29 taper downwardly to a point slightly below the outer edge of the lip 19. After securing the glass plate 26 in place by means of the clips 29, any suitable form of cement or putty 33 may be forced into the joints to produce a liquid and air-tight seal.

In order to secure a fly screen 27 or other panel in the metal frame 15, a plurality of resilient strips of convex metal 34 may be employed, one for each side member of said frame. The strips 34 are U-shaped in cross-section (see Fig. 5) and are provided with a plurality of spaced lugs 35 extending inwardly to cooperate with the slots 28 in the lips 19. Preferably, the screen 27 will be provided with a protective edge binding 36 extending around its periphery. The U-shaped strips 34 are adapted to fit against the webs 20 with the convex portions 37 thereof extended inwardly away from said webs. The edge of each convex strip 34 is adapted to lie between the web 20 and the outer edge of the screen 27, but terminates short of the flange 21 (see Fig. 5). The convex strips 34 are preferably made of spring metal, whereby they may be snapped over the lip 19 into the position shown in Fig. 5, and then will securely press the screen 27 against the flange 21.

Operation

When it is desired to convert a storm sash into a window screen, it is merely necessary to unfasten the hooks 23 from the pins or screws 25 and remove the glass-holding frames 15 from the openings 17 in the common frame 11. The screen-holding frames 15 may then be inserted into the openings 17 and securely locked in place by swinging the hooks 23 to catch about the pins 25.

While the common receiving frame 11 has been herein shown as having four openings, it will be understood that two or any other number of window openings may be provided within the spirit and scope of this invention.

One advantage of the present invention lies in the novel forms of glass and screen retaining means constituted respectively by the clips 29 and the convex strips 34, both of which have means thereon adapted to be received in the slots 28 in the lips 19 of the metal frames 15. This construction permits either glass plates 26, screens 27, or other panels to be assembled at will in the metal frames 15, necessitating the manufacture of only one style of frame 15.

While there has been disclosed in this specification one form in which the invention may be embodied, it will be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a convertible storm sash and fly screen, a main frame having an opening therein with a curved forwardly directed bead surrounding the edge of the opening, a removable second frame having a curved outer edge adapted to fit said bead, and a web portion shaped to seat upon the inner edge surface of the opening in said main frame, a plurality of swingable hooks pivoted to said removable frame, and a corresponding num-

ber of pins secured to said main frame for engagement with said hooks.

2. In a convertible storm sash and fly screen, a main frame having an opening therein with a curved forwardly directed bead surrounding the edge of the opening, a removable second frame having a curved outer edge adapted to fit said bead, and a web portion shaped to seat upon the inner edge surface of the opening in said main frame, a plurality of swingable hooks pivoted to said removable frame, and a corresponding number of pins secured to said main frame for engagement with said hooks, said second frame having a lip extending from said web portion, and a flange spaced from said lip and extending from said web portion parallel to said lip to receive a removable panel therebetween, and means to clamp said panel in place between said lip and flange.

3. In a convertible storm sash and screen, a main frame having an opening therein, said opening having a convex bead surrounding the edge thereof, a pair of interchangeable panel-holding metal frames each having a curved outer edge adapted to seat upon said bead and a web portion adapted to seat upon the inner edge of said opening, means to selectively secure said metal frames within said opening, each metal frame having a lip extending from the web portion thereof, a flange spaced from said lip and extending from said web portion and parallel to said lip, said flange serving as a seat for a panel for filling said opening, and means cooperating with said lip to secure the selected metal frame in place.

4. In a convertible storm sash and screen, a metal panel-holding frame having a convex outwardly extending flange about its front edge, a lip extending inwardly therefrom, a web extending at right-angles from the base of said lip, and a flat flange extending inwardly from said web parallel to said lip, said lip having perforations spaced apart along its length, and a plurality of flanged clips for engaging a panel disposed in said frame between said lip and said flange, said clips also having locking lugs adapted to enter said perforations.

5. In a convertible storm sash and screen, a metal panel-holding frame having a convex outwardly extending flange about its front edge, a lip extending inwardly therefrom, a web extending at right-angles from the base of said lip, and a flat flange extending inwardly from said web parallel to said lip, said lip having perforations spaced apart along its length, and a resilient convex strip having an edge adapted to embrace the edge of the panel disposed in said frame and located between said lip and said flange, said resilient strip having lugs spaced along its length adapted to enter said perforations, said strip being of spring metal adapted to yield and permit said panel to be snapped behind it.

6. In a convertible storm sash and fly screen, a main frame having a flanged opening, a removable second frame shaped to fit said opening and rest upon the flange thereof, said main frame having a plurality of upstanding pins arranged at spaced points about its perimeter and extending parallel to the plane of said main frame, and said second frame having a plurality of swingable hooks at right-angles to the plane of said second frame and located between the edges of both frames for releasable engagement with said pins to hold said second frame detachably in position within said main frame.
